SOUND REPRODUCING APPARATUS

Royden C. Sanders, Jr., Audubon, N. J., assignor
to Radio Corporation of America, a corporation
of Delaware

Application November 30, 1940, Serial No. 367,889

9 Claims. (Cl. 179—108)

This invention relates to sound reproducing apparatus, and more particularly to loudspeakers, the primary object of my invention being to provide a novel loudspeaker for converting electrical energy into acoustical energy and in which the power which generates the sound is not taken, to any appreciable extent, from the electrical input to the vibrating parts thereof.

More particularly, it is an object of my invention to provide a novel loudspeaker in which the electrical input controls the sound output in somewhat the same way that the grid electrode of an electron discharge device controls the plate current.

Another object of my invention is to provide a novel loudspeaker as aforesaid wherein a much smaller vibrating element is required, for a given power output at a given low frequency, and with less electrical audio input power, than is required with conventional loudspeakers.

A further object of my present invention is to provide a novel loudspeaker as aforesaid which has relatively small baffle requirements.

Still a further object of my invention is to provide a novel loudspeaker which has greatly improved transient response over conventional loudspeakers.

It is also an object of my invention to provide a novel electro-mechanical loudspeaker in connection with which high power audio amplifiers will not be required.

Another object of my invention is to provide a novel loudspeaker as aforesaid which has a uniform frequency response.

Still another object of my invention is to provide a novel loudspeaker as set forth above which is capable of reproducing sound with high fidelity.

A further object of my invention is to provide a novel loudspeaker which is fairly simple in construction, highly efficient in use, and of relatively small cost, particularly when considered from the standpoint of economy of operation and efficiency.

The novel speaker constituting my present invention may be designated as a "fan type loudspeaker," and its construction and operation, according to one form thereof, is as follows: A set of peripherally mounted blades is carried by a suitable suspension and rotated at a very high speed by a conventional electric motor. The blades are so mounted that they are adjustable in pitch but will generate no torque about their respective axes regardless of the angle at which the blades are set. The amount of air that the

fan blades push forward or pull backward will, of course, depend upon the instantaneous pitch of the blades. Coupled to the blades for altering their pitch in accordance with signal energy is an electro-mechanical driver, the pitch or angle of attack of the blades being determined by the instantaneous voltage applied to the driver. Since the instantaneous sound pressure generated by the blades varies as the instantaneous pitch thereof, it follows that a sound corresponding to the applied audio voltage will be generated by the blades.

The blades are preferably made of some suitable flexible, resilient material and are arranged circularly about a common axis, each blade being mounted for twisting movement out of its plane on a radial axis, so that its pitch can be varied. As noted heretofore, their axes are so chosen and the blades are so designed that no torque is generated about their respective axes at any pitch of the blades and even at full speed rotation of the fan. Thus, it is apparent that the unit may be so designed that the instantaneous pressure developed is directly proportional to the instantaneous audio voltage applied to the electro-mechanical driver. It is also apparent that the acoustical power generated will come mainly from the power developed by the electric motor which rotates the fan unit, and the portion of the acoustical power converted from the electrical audio input is very inappreciable. As a matter of fact, the work which the audio electrical power must do is mainly in overcoming the small amount of residual radiation resistance present even when the blades are not rotating plus the loss in the electrical driving circuit necessary in supplying the required power at poor power factors. The effect of reflected sound, such as may be obtained from trapping the backward radiation, is inappreciable upon the electrical input circuit or upon the position of the blades on their radial axes, and as a result of this, much smaller baffles may be used with my novel loudspeaker than has been required heretofore with conventional speakers.

The novel features that I consider characteristic of my invention are set forth with particularity in the appended claims. The invention, itself, however, both as to its organization and method of operation, as well as additional objects and advantages thereof, will best be understood from the following description of several embodiments thereof, when read in connection with the accompanying drawings in which Figure 1 is a side elevation, partly in section,

showing one form of loudspeaker constructed in accordance with my present invention.

Figure 2 is a front elevation of one form of diaphragm and mounting therefor according to my present invention.

Figures 3, 4 and 5 are fragmentary views similar to Fig. 1 showing other modifications of my invention.

Figure 6 is a fragmentary view similar to Fig. 1 showing another form of loudspeaker employing the principle of my present invention.

Figure 7 is a fragmentary front elevation showing a portion of the diaphragm and blades thereof employed in the loudspeaker of Fig. 6, and

Figures 8 and 9 are fragmentary front elevational views of a diaphragm somewhat similar to that shown in Fig. 2 but employing different blade mountings.

Referring more particularly to the drawings, wherein similar reference characters designate corresponding parts throughout, there is shown, in Fig. 1, a more or less conventional electric motor 1 to the casing of which is fixed a stationary cage or drum 3 and to the rotor 5 of which is secured a spider-like cage of wire or the like 7, so that the cage 7 rotates with the rotor 5 at a relatively high speed. The cage 7 carries a pair of annular clamping rings 8 between which a vibratable unit 11 is clamped and supported for vibration, the clamping rings 8 being provided with a plurality of inwardly directed, radially extending and circumferentially spaced saw-tooth projections 13 for a purpose presently to be set forth.

The vibratable member 11, as shown more clearly in Fig. 2, is preferably made of relatively thin, flexible, resilient material, such as mica, aluminum, paper, paper pulp, synthetic resin, or the like, in sheet form and may be stamped or cut out from the sheet in one piece by a suitable die which slots the sheet radially outwardly from a central hub 15 along the slots 16 to provide a plurality of discrete, substantially contiguous, wedge-shaped blades 17. The cutting die preferably also removes portions 18 from adjacent the periphery of the sheet to provide the radially extending tails 21 at the outer ends of the blades 17. The saw-tooth projection 13 on the clamping rings 8 correspond in number to and are circumferentially spaced the same angle as the tails 21 and serve to clamp the tails 21 therebetween. It will be obvious, therefore, that displacement of the hub 15 along the axis of the rotor 5 from the position which the hub 15 normally occupies at rest will cause the blades 17 to twist out of their common plane along radial axes passing through the centers of the tails 21 by reason of the fact that the inclined edges of the saw-teeth 13 extend across the radial axes passing through the tails 21 at an angle thereto. Movement of the hub 15 to the right, as seen in Fig. 1, will cause the blades 17 to twist in one direction, and movement of the hub 15 to the left, as seen in Fig. 1, will cause the blades 17 to twist in the opposite direction.

For effecting displacement of the hub 15, there may be mounted on the drum 3 any suitable electro-mechanical driver, such as the electrodynamic unit constituted by the field structure 23 and the voice coil 25 carried on a spider 21, the spider 21 also having secured thereto an open-ended cap member 29 which fits loosely over and around a hollow cap 31 secured to the hub 15, the loose fit of the cap member 29 around the cap 31 pro-

viding a thin annular air space 33 between the cylindrical portions of the two caps (exaggerated in the drawings as to thickness for the sake of clearness) and a fluid column 35 between the ends thereof. When signal voltages within the audio frequency range are applied to the voice coil 25, the cap member 29 is displaced from its normal position and, through the column of air in the space 33, drives the cap 31 and the hub 15. This causes the blades 17 to twist correspondingly while the member 11 is being rotated at a high speed by the motor 1 and, in turn, effects air displacement at acoustical frequencies.

Fig. 3 illustrates a construction similar to that shown in Fig. 1, but instead of employing the electrodynamic driver 23-25, an electro-magnetic driver 37 may be mounted on the drum 3 for cooperation with a soft iron armature 39 secured to the hub 15. Signal voltages applied to the coils 41 of the driver 37 will cause the associated cores to more or less attract or repel the armature 39 in well-known manner and thus effect vibration of the hub 15 and corresponding rotation or twisting of the blades 17 on their respective axes to alter their pitch at acoustic frequencies.

In the modifications of Figs. 1 and 3, the drivers 23-25 and 37 are mounted on the drum 3 and are therefore stationary. Since the diaphragm 11 rotates, it is necessary to provide a loose coupling between the drivers of these modifications and the hub 15 of the diaphragm 11, and it is for this reason that the air spaces 33 and 35 are provided in the modification of Fig. 1 and the air gap between the cores of the electromagnets and the armatures 39 are provided in the form of my invention shown in Fig. 3. In some cases, it may be desired to provide a rigid coupling between the driver and the diaphragm 11, and in such cases, it is necessary that the driver shall rotate with the diaphragm. A construction which operates in this manner is shown in Fig. 4 wherein the driver 43, which may be of any suitable type, such as an electromagnetic, electrodynamic, condenser, piezoelectric crystal driver, or the like, is formed with a hub 45 by means of which it is secured to the rotor 5, the cage 7 being fitted over the hub 45, and the rotor 5, the cage 7 and the hub 45 all being secured together for rotation as a unit. A rigid coupling, such as a driving rod 47, may be suitably secured to the vibratable member 11 at the hub portion 15 thereof to effect the desired coupling between the driver 43 and the vibratable member. Since the driver 43 rotates with the rotor 5, the drum 3 may be entirely eliminated. To provide input leads to the driver 43, the rotor 5 may be made hollow and the input leads 49 brought in through the rotor.

Where practical considerations dictate mounting the driver on the stationary frame or drum 3 and a rigid coupling is desired between the driver and the member 11, a construction such as that shown in Fig. 5 may be employed. In this modification, the driver 43 is mounted on the drum 3, as in the modifications of Figs. 1 and 3, and the hub portion 15 of the diaphragm 11 is provided with a small opening 51. The coupling rod 47 between the driver 43 and the hub portion 15 is provided with a jewel bearing member 53 which fits into the opening 51. On the other side of the member 11, the rotor 5 is formed with a reduced end 55 and axially aligned with the rotor portion 55a is a pin 55 which also carries a jewel bearing 57 fitted into the opening 51. A coil

spring 59 is interposed between the rotor 5 and the bearing 57 around the rotor portion 5a and the pin 55 and serves to press the bearing 57 against the hub portion 15 and the latter against the bearing 53. A space 61 is, of course, provided between the ends of the rotor portion 5a and the pin 55 to permit vibration of the diaphragm 11 in response to the signal voltages applied to the driver 43.

In the modifications of my invention thus far described, use is made of mechanical means to effect vibration or twisting of the blades 17. Another method of changing the angle of the fan blades 17 with the applied signal voltage is shown in the modification illustrated in Fig. 6. In this modification, the cage 7 is omitted and the hub 15 of the member 11 is secured to the rotor 5, the clamping rings 9 being secured to the tails 21 of the fan blades 17. One-half of each of the blades 17 is coated with a conducting material 63, as clearly shown in Fig. 7, the material 63 being applied by spraying or in any other suitable manner, and the conducting material 63 contacting the clamping members 9 and being connected thereby to ground, as by means of one or more conductors 64 connecting the members 9 to the grounded rotor 5. The conductors 64 are preferably uniformly distributed circumferentially about the rings 9 and pass radially outwardly from the rotor 5 to the rings 9 over suitable ones of the slots 16 in the member 11, so as not to interfere with the vibration of the blades 17. For this purpose, the slots 16, in this modification of my invention, may be made somewhat wider than in the other modifications. The blades in this modification are twisted or deflected about their respective axes by an electrostatic force obtained from a pair of fine mesh wire screens 65 carried on the drum 3 on each side of the member 11 and to which the audio driving signals are applied through a step-up transformer 66. The screens 65 are supplied with a suitable polarizing potential by means of a battery 68 connected between the mid-tap of the secondary winding of the transformer 66 and the drum 3 which is grounded on the casing of the motor 1, the arrangement being similar to that shown, for example, in the Lee patent, No. 1,622,039. This system has the advantage of having a very good electro-mechanical coupling that does not involve slip rings although requiring a step-up transformer for the driving voltages and a high polarizing voltage source.

In Figs. 8 and 9, there are shown modified forms of fan blade assemblies. Instead of stamping the assembly out of a single sheet member 11, as described above, the substantially wedge-shaped blades 17 may be individually stamped out and provided with a tail at each end. The outer tails 21 are clamped, as before, between the saw-tooth projections 13 of the clamping rings 9, and the inner tails 21a are clamped between the saw-tooth projections 67 of a pair of discs 69 which take the place of the hub portion 15 in the modifications previously described. The angular edges of the saw teeth 13 and 67 may be made parallel to each other, as shown in Fig. 8, or they may be angularly related as shown in Fig. 9. In any case, upon displacing the discs 69 from their normal, rest position, it will be obvious that the blades 17 will be twisted in the manner described above.

From the foregoing description, it will be apparent to those skilled in the art that I have provided an entirely novel loudspeaker which has

the many advantages heretofore set forth. As shown in Fig. 2, the vibratable member 11 is formed with sixteen blades. However, it will be apparent that any number of blades may be employed. In designing the vibratable member and the mounting therefor, it should be kept in mind that the resonant frequency of the vibrating system is determined to a large extent by (1) the rotational inertia of the individual blades 17, (2) the mass of the center clamping members, such as the discs 69, and (3) the stiffness presented by the blade suspensions at the tails 21 and 21a. In general, it may be stated that the use of as many fan blades as possible is desirable. Also, the blades should preferably be made of the highest and strongest materials possible.

Although I have shown and described a number of modifications of my invention, it will be apparent to those skilled in the art, that many other modifications, as well as changes in those described, are possible. I therefore desire that my invention shall not be limited except insofar as is made necessary by the prior art and by the spirit of the appended claims.

I claim as my invention:

1. In a sound translating device, the combination of a rotatable member, means for rotating said member on a predetermined axis, and means for simultaneously variably rotating said member about another axis angularly related to said first named axis and at frequencies within the audible range.

2. In a sound translating device, the combination of a vibratable member, means for rotating said member about a predetermined axis, and means for oscillatably twisting said member about an axis substantially normal to said first named axis and at frequencies within the audible range.

3. In a sound translating device the combination of a vibratable member comprising, as a unit, a hub and a plurality of discrete blades extending radially with respect to and spaced circumferentially about said hub, a motor coupled to said unit for rotating said unit, means mounting each of said blades for twisting movement thereof about an axis in the plane thereof, said blade axes also being radially related to said hub, and a second motor responsive to audio-frequency impulses coupled to said unit for twisting said blades about their respective axes whereby to vary the pitch of said blades relative to said hub at audio frequencies.

4. In a sound translating device, the combination of a vibratable member comprising, as a unit, a hub and a plurality of discrete blades extending radially from and spaced circumferentially about said hub, a motor coupled to said unit for rotating said unit, means mounting each of said blades for twisting movement thereof about an axis in the plane thereof upon displacement of said hub from its normal position, said blade axes also being radially related to said hub, and a second motor responsive to audio-frequency impulses coupled to said hub for displacing said hub from its normal position at frequencies within the audio spectrum whereby to correspondingly twist said blades about their respective axes and thereby correspondingly varying the pitch of said blades relative to said hub.

5. The invention set forth in claim 4 characterized in that said hub and said blades are constituted by an integral piece of flexible and resilient sheet material slotted radially from said hub at a plurality of circumferentially spaced points.

6. The invention set forth in claim 4 characterized in that each of said blades terminates in a relatively narrow tail along the axis of the blade, and characterized further in that said mounting means is constituted by a pair of clamping members having a plurality of cooperating saw-tooth projections thereon between which said tails are clamped, said saw-tooth projections being angularly related to the axes of their respectively associated blades.

7. The invention set forth in claim 4 characterized in that said mounting means includes a pair of cooperating clamping rings to which the marginal portions of said blades are secured, and characterized further in that said first named motor includes a rotor element coupled to said clamping rings.

8. The method of effecting air displacements within the audio frequency range which comprises rotating a member on a predetermined axis, 20

and simultaneously variably rotating said member at audio frequencies about a second axis normal to said first named axis.

9. In signal translating apparatus, the combination of a diaphragm comprising a normally plane member having a hub portion and a plurality of substantially wedge-shaped portions extending radially outwardly from said hub portion, said wedge-shaped portions being slightly spaced from each other in a direction circumferentially around said hub portion and being movable relative to said hub portion, each of said wedge-shaped portions having an extension thereon extending radially outwardly from its periphery, and clamping means including elements engaging said extensions and confining movement of said wedge-shaped portions to rotation each on a radial axis passing through its extension.

ROYDEN C. SANDERS, JR.
